UNITED STATES PATENT OFFICE.

CARL F. HAAS, OF SOUTH BEND, INDIANA, ASSIGNOR TO WESTINGHOUSE ELECTRIC
AND MANUFACTURING COMPANY, A CORPORATION OF PENNSYLVANIA.

DESIGN FOR A SIGNAL BRACKET.

Application filed March 15, 1928. Serial No. 25,858. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for Signal Brackets, of which the following is a specification, reference being had to the accompanying drawings, constituting a part hereof.

Figure 1 is a side elevational view of a signal bracket showing my new and ornamental design;

Fig. 2 is a top elevational view thereof, the dotted line portions being shown for the purpose of disclosing the manner in which the signal bracket is used.

I claim:

The ornamental design for a signal bracket substantially as shown.

In testimony whereof, I have hereunto subscribed my name this 29th day of February, 1928.

CARL F. HAAS.
